JOSEPH M. PRUGGER, OF NEW YORK, N. Y.

Letters Patent No. 65,503, dated June 4, 1867.

IMPROVEMENT IN BUTTONS.

The Schedule referred to in these Letters Patent and making part of the same.

TO ALL WHOM IT MAY CONCERN:

Be it known that I, JOSEPH M. PRUGGER, of the city, county, and State of New York, have invented a new and improved Button; and I do hereby declare that the following is a full, clear, and exact description thereof, which will enable others skilled in the art to make and use the same, reference being had to the accompanying drawings, forming part of this specification.

Figures 1, 3, and 5 are side views of my improved button.

Figures 2 and 4 are bottom views of the same.

Similar letters of reference indicate corresponding parts.

The object of this invention is to construct a button, with its fastening secured to it, in such a manner that the said button may be easily applied to or detached from the cloth at will, and may be firmly held thereon, without injuring the material.

The invention consists in the use of a spirally wound pointed wire, which is secured to the under side of the button, and which is screwed into the cloth, when the button is to be fastened thereto. For better fitting the button to the cloth, I also provide a downward extension or base for the button, which base remains in the button-hole when thus used.

A is the button, which is provided with a base, α , between which and the body of the button a neck, δ , may be left, as shown in fig. 1, or which may taper downwards, as in fig. 5. To the base α I securely fasten, either by soldering, pressing, or by any other suitable method, a metal wire, c , which extends in a straight line, and at a more or less obtuse angle, only in proportion to the thickness of the cloth; and is then bent in a spiral line until it has the required diameter. This same wire can be applied to buttons without a base, as is shown more clearly in fig. 3. It will be observed that the spiral portion of the wire is perfectly horizontal, not deviating from a perfect level, and that its end is pointed, so that it may easily be passed through the cloth.

I am aware that spiral wires are already used on buttons for the same purpose; but they are always wound similar to a cork-screw, the lowest sharp point being further from the lower surface of the button than any other part of the wire. These wires project too far beyond, and cannot be used practically, while my button can be easily applied and firmly held in any part of the garments, whether the materials be thick or thin, without any inconvenience to the wearer or detriment to the material.

When the button is to be applied, the point of the wire c is passed through the cloth, and the button is then turned until either the whole wire has been passed through the cloth, or until a part of the windings have penetrated the cloth, the cloth being, in the latter case, firmly held between the spiral windings of the wire. The windings of the wire may be varied at pleasure, and I do not wish to confine myself to any particular one of them.

I am aware that the attachment of buttons by means of coils is not new, and that the coil has been seated in a hollow shank and collet. These devices I do not claim. But what I do claim, and desire to secure by Letters Patent, is—

A button, having a shank whose base α is concave, in the centre of which is secured, at an obtuse angle, the wire coil c , whose convolutions are in the same plane with the base, whereby the button is uniformly supported while holding the cloth clamped in the concavity of the base, substantially as described.

JOSEPH M. PRUGGER.
